ACTION DISPLAY DEVICE

Charles L. Kee, Brooklyn, N. Y., assignor to William J. O'Hear, Jackson Heights, N. Y.

Application March 28, 1949, Serial No. 83,834

3 Claims. (Cl. 40—126)

1

This invention relates to an action display device and more particularly to a device of this class in which a fluid body is visibly transferred from one element of the display to another.

Heretofore, action display devices of this general class have embodied a free flowing fluid for visible discharge from one transparent receptacle into another, but these devices have usually completely drained the storage receptacle into the receiving receptacle or the discharge has been from a concealed source of supply into a receiving receptacle.

It is, therefore, an object of this invention to create a completely realistic illusion of the pouring of liquid or the like from one transparent receptacle to another by permitting only a portion of the fluid to be drained from the supply receptacle. It is also an object of the invention to provide a device in which the receiving receptacle is only comfortably filled, thereby imparting greater realism to the illusion. Specifically, the invention is illustrated in connection with a transparent pouring receptacle from which liquid is supplied to a transparent receiving receptacle and wherein a quantity of liquid is retained in the pouring receptacle and the receiving receptacle is filled to a depth slightly below the rim thereof.

The fuller nature and further objects of the invention will become apparent as the description thereof is read with regard to the drawing forming a part hereof, and in which drawing:

Fig. 1 is a face view of an action display panel,

Fig. 2 is a front view thereof with the covering panel removed to show underlying structure, and

Fig. 3 is a vertical sectional view through the device.

The display device relates particularly to that class wherein a panel 10 is provided for periodic reversal or inversion about its transverse axis to render the action visible. The panel 10 includes a framework 12, herein shown as substantially rectangular. Extending between two opposite sides of the framework 12 is a supporting base 14 to which are affixed the fluid receiving receptacles 16 and 18, herein illustrated as being formed as a unitary structure although not necessarily so constructed.

The first fluid containing receptacle 16 is inclined horizontally within the plane of the framework 12 so that when the panel is positioned in a substantially vertical direction, the mouth of the receptacle 16 is at the lower point of inclination.

The fluid receiving receptacle 18 is positioned

2

in a substantially vertical manner on the supporting base 14 and has its mouth located at a point below the mouth of the receptacle 16. A conduit 19 interconnects the receptacles 16 and 18 whereby the fluid therein may pass from one receptacle to the other. A restricting valve 20 may be placed in the throat of the receiving receptacle 18 in order to limit the flow from the receptacle 16 into the receptacle 18 to a relatively slow stream and for the further purpose of spreading the stream in a realistic manner.

One of the important features lies in the relative proportions of the receptacle 16 and the receptacle 18. The receptacle 16 is larger than the receptacle 18 and in the discharge passage thereof is provided a weir 22 which limits the amount of fluid that is permitted to escape from the receptacle 16 to the receiving receptacle 18 while the panel is in a substantially vertical position. The receptacles 16 and 18 may be transparent in whole, or may have applied to one or both sides thereof a transparent window as, for example, the window 24 which covers the cavity of the receptacle 16 and the window 26 which covers the cavity of the receptacle 18.

To one or both faces of the framework 12 is attached a pictorial representation 28 which has one or more transparent areas adapted to overlie one or both of the fluid holding receptacles within the frame. Specifically, the representation illustrated herein is that of a person pouring a liquid from a bottle 30 into a glass 32. At least a portion 34 of the bottle 30 is transparent so that the liquid within the receptacle 16 is visible from the face of the pictorial representation of the display device.

Similarly, a portion 36 of the glass 32 is also transparent and this transparent portion overlies the transparent portion 26 of the underlying receiving receptacle 18.

Herein the panel 10 has illustrated a pictorial representation on only one face thereof, the cover or facing on the opposite side having been omitted to facilitate illustration. It is contemplated, however, that both faces of the panel will be enclosed. The rear face panel may have only intelligence thereon or a further pictorial representation in which the reverse flow of the fluid from the receptacle 18 into the receptacle 16 is utilized for imparting action when the panel is rotated about its transverse axis to bring into view the opposite face thereof, the device being supported in a vertical position for rotation about its transverse axis on suitable horizontally supporting elements 38, 38.

With the mechanism as described, it will be seen that when that face of the panel illustrated in Fig. 1 has been presented to view by rotating the same on its transverse axis, there will be presented the illusion of liquid flowing from the bottle 30 into the glass 32. The fall of the liquid level in the bottle 30 can be observed through the transparent portion 42 while at the same time the rise of the liquid level in the glass 32 can be observed through the transparent portion 34. The greater realism is imparted to the display device by the fact that the weir 22 permits only so much liquid to enter the receptacle 18 so as to fill the same to a point somewhat short of the lip of the glass 32 which overlies the receptacle 18. At the same time the weir retains liquid within the receptacle 16 so as to give the illusion of residual liquid within the bottle, substantially to the level visible through the transparent portion 34 of the representation. Upon subsequent rotation of the panel 10 about its transverse axis the fluid will drain from the receptacle 18 and will again repose in full in the receptacle 16.

While the invention has been described specifically in connection with a display device representing the pouring of liquid from a bottle to a glass, the invention may be embodied in other representations without departing from the spirit of the claims that are to follow.

I claim:

1. In an action display device, a framework, a support within said framework, a first fluid receptacle fixed to said support, a second fluid receptacle of smaller size fixed to said support, a fluid conduit interconnecting said receptacles, a free flowing fluid substantially filling said first receptacle, a weir in said conduit for limiting the flow of fluid from said first receptacle into said second receptacle to a volume slightly less than the capacity of said second receptacle, and a pictorial representation on the face of said framework having transparent portions overlying said receptacles.
2. In an action display device adapted for display in a substantially vertical position, a framework, a first fluid receptacle positioned within said framework and inclined downwardly, a second substantially smaller fluid receptacle positioned within said framework below the lower end of said first receptacle, a fluid conduit intercon-

necting the lower end of said first receptacle with said second receptacle, a free flowing fluid of sufficient volume to substantially fill said first receptacle within said first receptacle, a substantially vertical weir in said conduit for limiting the flow of fluid from said first receptacle into said second receptacle to a volume slightly less than the capacity of said second receptacle, and a pictorial representation on at least one face of said framework having transparent portions overlying said receptacles.

3. In an action display device adapted for display in a substantially vertical position, a framework, means to support said framework in a vertical position for rotation about a transverse axis, a first fluid receptacle positioned within said framework and inclined downwardly, a second substantially smaller fluid receptacle positioned within said framework below the lower end of said first receptacle, a fluid conduit interconnecting the lower end of said first receptacle with said second receptacle, a free flowing fluid of sufficient volume to substantially fill said first receptacle within said first receptacle, a substantially vertical weir in said conduit for limiting the flow of fluid from said first receptacle into said second receptacle to a volume slightly less than the capacity of said second receptacle, and a pictorial representation on at least one face of said framework having transparent portions overlying said receptacles.
